UNITED STATES PATENT OFFICE

2,354,839

BUS OR CAR WINDOW CONSTRUCTION

Joseph Schunk, Union, N. J., assignor to The National Lock Washer Company, Newark, N. J., a corporation of New Jersey

Application January 19, 1942, Serial No. 427,342

2 Claims. (Cl. 189—72)

The present invention relates to improvements in bus or car window construction, and particularly to the slide channels or runways in which the vertical side edges of the window sash are engaged for sliding raising and lowering movement. With this type of sliding sash it is necessary, in order to permit the sash to be operated with ease, while at the same time providing a structure in which normal manufacturing tolerances are permissible, that clearances be maintained between the parts, these clearances being normally sealed by means of suitable rubber and felt sealing means. It has been found that heavy rain forced against the outside of bus window structures of this type, even in the case of structures wherein great care has been taken to produce a good window seal with the window sill, when the window is closed, finds its way through some of the small openings or spaces existing between some of the contacting and relatively movable members. Quite often in doing this, the rain water builds up in the space within the post piece assembly back of the vertical side edge of the window sash, and in time this rain water builds up sufficiently to cause objectionable leaks through to the inside of the bus.

It is obvious that a sash made to fit tightly into the side channels or runways would, of course, tend to reduce in size or eliminate some of the openings or spaces through which rain under pressure would be admitted to the back inside portion of the runway, but such tightness would result in a sash that would be extremely difficult to raise and lower, and would furthermore not compensate for the expansion and contraction effect of extreme temperature changes. Reducing tolerances and overcoming size and cross-sectional variations of parts and assemblies would eliminate or reduce objectionable small openings or spaces, but the manufacturing cost of such a structure would become prohibitive, and furthermore the maintenance of a perfect fit, when the window is in service and subjected to varying degrees of strain and rough treatment, would not be reasonably possible.

An object of the invention is to provide a window structure having means for permitting drainage to the outside of rain water which accumulates in the post piece assembly, and to provide a novel structure in relation to the drain opening whereby accumulated water will be caused to flow toward such drain opening and will be prevented from reaching parts of the assembly whereby it could leak inside the bus.

A further object is to provide drain opening

means so arranged with relation to the outside window sill that the backwash of the rain water on the sill, such as is produced by the combination of wind, rain and forward motion of the bus, will be prevented from flowing through the drain opening to the interior of the post piece assembly.

With the above and other objects in view, embodiments of the invention are shown in the accompanying drawings, and these embodiments will be hereinafter more fully described with reference thereto, and the invention will be finally pointed out in the claims.

In the drawings:

Fig. 1 is a side elevation of the lower left hand corner of a bus or car window construction, showing the cooperative post piece assembly in which the sash is engaged.

Fig. 2 is a vertical sectional view through the window sash and sill, the section being taken 20 along a line substantially centrally of the window sash.

Fig. 3 is a horizontal sectional plan view, taken along the line 3—3 of Fig. 2.

Fig. 4 is a horizontal sectional plan view, taken 25 along the line 4—4 of Fig. 2.

Fig. 5 is a vertical sectional view, taken along the line 5—5 of Fig. 4.

Fig. 6 is a side elevation of the post piece and cooperative window sill structure, the window sash, the rack supporting channel piece and the 30 outside stop member being removed.

Fig. 7 is a vertical sectional view, taken along the line 7—7 of Fig. 6.

Fig. 8 is a side elevation of the lower end portion of the rack supporting channel member, removed from the post piece.

Fig. 9 is a side elevation of the lower left hand corner of the window sash, removed from the post piece.

Fig. 10 is a horizontal sectional plan view, taken 40 along the offset line 10—10 of Fig. 7.

Fig. 11 is a horizontal sectional view of the lower end of the rack supporting channel member, taken along the line 11—11 of Fig. 8.

Fig. 12 is a side elevation of the lower end of the removable outside stop member, removed from the fixed inside stop post piece assembly as shown in Fig. 6.

Fig. 13 is a horizontal sectional view, taken 50 along the line 13—13 of Fig. 12.

Fig. 14 is an inside elevation of the removable stop member.

Fig. 15 is a horizontal sectional view of a modified form of the invention, in which the post piece 55 is of the type having an inside removable stop.

Similar reference characters indicate corresponding parts throughout the several figures of the drawings.

Referring to the drawings, the window sash part of the bus or car window structure, in which the invention is incorporated by way of example, comprises a sash glass 10 having a top rail (not shown), a bottom rail 11, and a pair of vertical side straps 12 connecting the top and bottom rails, only the lower end of one of these side straps being shown. The side straps are adapted to have vertical sliding movement in the channels or runways mounted on the side posts, hereinafter more fully referred to. Each of the side straps 12 is in the form of a U-shape cross-section channel and is adapted to receive the marginal side edge of the glass, the vertical edges of the strap being bent outwardly and rearwardly, as at 13-13, to engage the edge of the U-shape cross-section strip of facing material 14, of felt composition or the like, which is cemented or otherwise suitably secured upon the side strap, to adapt it to have easy sliding engagement in the side post channel assembly.

At the lower end of the side strap 12 there is rigidly secured by welding, or other suitable means, a right angularly extending rectangular cross-section tubular member 15 about which is secured a tubular sheath member 16, and which two tubular members constitute a rigid securing bar member for securing the bottom rail 11 to the side strap, this bar member being insertable in the longitudinally extending space 17 of the bottom rail where it is rigidly secured by means of screws 18. One of these screws 18 may preferably be one of the screws for attaching the casting 19 of the latch member 20, which is connected to a spring-pressed bolt member 21, slideable in the tubular member 15 and having its nose portion projected through a slot 22 in the strap 12 and in the facing 14, this bolt member adapted to cooperate with the rack in the channel assembly for supporting the window in adjusted open positions, and being retractable by operation of the latch 20.

The bottom rail 11 is provided at its underside with a sealing strip attaching channel 23, having longitudinal inwardly bent flanges 24 at each side, and in which is engaged in interlocking relation a rubber sealing strip 25 for engaging the window frame sill 26 in sealing relation, the ends of this sealing strip 25 extending into vertically aligned flush relation with the vertical end surfaces of the facing strip 14 at each side edge, for the purpose of having sealing engagement with a rubber sealing member carried in the channel assembly at each side, as will presently more fully appear.

The channel assembly in which the window sash is slidably mounted is carried upon the side post 27 of the window frame in abutting relation against a vertically extending flange 28 provided at the inner side of the post, and which abuts against an upwardly projecting flange 29 provided along the inner edge of the sill 26. The channel assembly comprises a fixed inside stop member 30 having a vertically extending forwardly bent base portion 31 and a forwardly disposed lip flange 32 formed of double thickness by bending the metal of the lip flange backwardly upon itself, as at 33, the edge of this backwardly bent portion being projected toward the side post 27. A strip of packing 34, which may be of felt, sponge rubber, or other suitable material, is engaged between the side post and the base 31 and projecting edge portion 33 of the fixed stop mem-

ber, the latter being secured to the side post by means of screws 35 engaged through holes in the base 31 and in the side post and screwed into retaining nuts 36.

5 The removable outside stop 37 is bent upon itself to provide an inner leg portion 38, disposed in spaced parallel relation thereto to form a recessed structure for straddling the lip flange 32 of the inside stop, the outside stop being provided 10 at suitable intervals, preferably near its upper and lower ends, with hook members 39, secured between its outer and inner leg portions by spot welding or other suitable means, and which are adapted to be wedgingly engaged in bayonet slots 15 40 provided in the lip flange 32 of the inside stop to thus secure the movable outside stop to the fixed inside stop. The outside stop is adapted to be fixedly secured in its engaged position by means 20 of a set screw 41 carried in its outer side and adapted to be screwed into a threaded hole 42 in the lip flange 32.

Within the channel formed by the inside and outside stops there is provided a rack carrying channel strip 43, preferably covered with a strip 25 of facing material 44, of felt composition or other suitable material and cemented thereto, and provided at its forward side with inwardly bent flanges 45 which engage the backing strip 14 of the window sash, the channel strip being yieldable pressed into engagement with this backing 30 strip by means of a series of bowed leaf spring members 46 secured upon the base 31 of the inside stop by screws 47. Within the channel strip there is provided a rack member 48 preferably welded in place, and which is adapted to be engaged by the latch bolt 21 carried by the base rail of the window sash. In the lower end of the channel strip there is interlocking secured a sealing block member 49, of rubber or the like, which projects slightly beyond the flanges 45 of the channel strip and is adapted to be tightly engaged by 40 the end of the rubber sealing strip 25 of the base rail in the closed position of the window sash.

In the lower end of the channel structure there is secured to the base portion 31 of the inside 45 stop member a block member 50 preferably formed of sponge rubber cemented in place, the inner vertical edge of this block member being engaged against and cemented to the inner surface of the inside stop and the outer forward 50 vertical edge being slightly spaced from the lip flange 32 to provide a recess in which the leg of the outside stop is adapted to be engaged. The upper surface of the block member is inclined downwardly from its rearward to its forward 55 edge. Adjacent the forward edge of the inclined upper surface of the block member 50, there is provided in the lip flange 32 a hole 51 for the purpose of providing an outlet drain passage for rain water which may collect in the channel 60 assembly and which flows along the inclined top surface of the block member 50 toward the hole 51.

The outside stop member is provided in its inner leg portion with a cut-out 52 having its lower edge arranged to be substantially in line with the forward edge of the inclined top surface of the block member 50 in the engaged relation of the outside stop, and which provides a passage for the rain water to flow from the inclined surface to and through the hole 51. The outside stop is provided at its outer portion with a slot opening 53 formed by slitting the metal and thereupon pressing the metal above the slot opening outwardly in the form of a rounded hood

54, so arranged that the rain water flowing through the hole 51 will flow against the inner side of the hood and be emitted downwardly through the slot opening 53, the hood at the same time protecting the slot opening against entrance of rain water from the outside. The slot opening 53 is arranged substantially above the sill 26 so that back-wash and splash upon the sill will not flow into the slot opening.

In Fig. 15 there is illustrated a modified form of the invention in which the water drainage means is incorporated in a channel assembly of the type in which the outside stop is fixed and the inside stop is removable. In this case, the side post 27^a is provided adjacent its outer side with a vertically extending abutment flange 28^a against which the outer portion of the fixed stop 30 is engaged, the lip flange 32 upon which the removable stop is engaged being disposed inwardly adjacent the flange 29 of the sill. The outer portion of the fixed stop is provided with a slit 53^a having a pressed out hood portion 54^a above it, in similar manner to the slit and hood of the first embodiment of the invention, the upper inclined surface of the rubber block member 50 having its lower end substantially in line with the slit 53 and the forward vertical surface of the block being secured by cementing to the inner surface of the outer portion of the fixed stop. The rearward vertical surface of the rubber block member 50 is spaced forwardly from the lip flange 32 to provide a space for receiving the inner leg 38 of the removable stop. The structure and operation of the channel assembly is otherwise similar to that of the first embodiment.

I have illustrated and described preferred and satisfactory embodiments of the invention, but it will be understood that changes may be made therein within the spirit and scope thereof, as defined in the appended claims.

Having thus described my invention what I claim and desire to secure by Letters Patent is:

1. In a window construction, a side post channel assembly including inner and outer stop portions and a base portion, and a window sash having a vertical side adapted to be engaged within said channel assembly in spaced relation

5 to said base portion with its inner and outer side surfaces engaged by said stop portions, the engagement between said outer side surface and said outer stop portion being frictional and presenting a water-pervious passage through which water driven transversely may pass to said space, and the engagement between said inner side surface and said inner stop portion being frictional and presenting a passage through which water collecting in said space may leak, said outer stop portion having a water drainage opening therethrough extending to the space between said window sash and said base portion whereby water entering said space through said water-pervious passage between said outer stop portion and the outer side surface of said sash drains outwardly through said drainage opening.

2. In a window construction, a side post channel assembly including inner and outer stop portions and a base portion, a window sash having a vertical side adapted to be engaged within said channel assembly in spaced relation to said base portion with its inner and outer side surfaces engaged by said stop portions, the engagement between said outer side surface and said outer stop portion being frictional and presenting a water-pervious passage through which water driven transversely may pass to said space, and the engagement between said inner side surface and said inner stop portion being frictional and presenting a passage through which water collecting in said space may leak, said outer stop portion having a water drainage opening therethrough substantially spaced above its lower end extending to the space between said window sash and said base portion, whereby water entering said space through said water-pervious passage between said outer stop portion and the outer side surface of said sash drains outwardly through said drainage opening, and filler means disposed within said space at the lower end thereof extending between said inner and outer stop portions having its upper surface inclined downwardly toward said outer stop portion and having its lower end substantially in line with said water drainage opening whereby water collecting in said space is directed toward said drainage opening.

JOSEPH SCHUNK.
